UNITED STATES PATENT OFFICE.

WILLIAM H. CADWELL, OF WILLIAMSTON, MICHIGAN.

MOLD FOR BUILDING CONCRETE OR CEMENT WALLS.

SPECIFICATION forming part of Letters Patent No. 710,749, dated October 7, 1902.

Application filed June 11, 1902. Serial No. 111,084. (No model.)

To all whom it may concern:

Be it known that I, WILLIAM H. CADWELL, a citizen of the United States of America, residing at Williamston, in the county of Ingham 5 and State of Michigan, have invented certain new and useful Improvements in Molds for Building Concrete or Cement Walls, of which the following is a specification, reference being had therein to the accompanying 10 drawings.

This invention refers more particularly to the art of building walls of cement; and it consists in a collapsible mold whereby cement walls of any thickness may be built with the 15 same appliances and whereby the outer face of the wall may be veneered at the same time with a coat of fine cement, while the interior of the wall may be built up with cement mixed with crushed stone, all as more fully set forth 20 hereinafter and shown in the accompanying drawings, in which—

Figure 1 is a perspective view showing a cement structure in the process of erection with the use of my wall-mold. Fig. 2 is a cross-section of Fig. 1. Fig. 3 is a detached perspective view of one of the false mold-plates, and Fig. 4 is a horizontal section on the line $x x$ of Fig. 2.

My wall-mold consists of moldboards A, 30 formed of loose boards or planks, and of binders B, each composed of two side bars a and of two adjustable tie-rods $b c$, transversely uniting the side bars in parallelism with each other. These tie-rods b and c pass loosely 35 through the wooden side bars, and the former is screw-threaded at both ends and clamps the side bars by means of screw-nuts d bearing against the inner and outer faces of the side bars, washers e being interposed between 40 the nuts and their bearing-faces. The tie-rod c is made adjustable upon one end only by a nut and washer f , the other end having a fixed head g . The object of this construction is to permit of spacing the side bars of 45 the binders B any distance apart within the limits of thickness usually given to cement walls and also to clamp the moldboards A tightly to the wall.

The use of my appliance is very simple and 50 will be readily understood from the illustration in Fig. 1, which shows the corner of a

building with cement walls in the course of construction. The mold as shown therein is formed of two planks (or rows of planks) placed against the outside face and two like 55 planks (or rows of planks) placed against the inner face and held together by means of binder-frames placed at intervals apart, all so arranged that the upper planks overtop the part already built and form a trough for filling in fresh cement between the two upper 60 planks.

By building the molds for all the walls of the building and proceeding systematically to raise the walls evenly up the height of one 65 board all around the work of raising the molds and filling in fresh cement may be carried out during the day-time, so that during the night-time the freshly-built portions will have time to set and harden. The progress made 70 in the erection of the building can be hastened by using wider planks, (or more planks on top of each other,) with the object of forming troughs of greater depth. With this *modus operandi* of construction door and window 75 frames may be placed in position while the walls are built up, and great facility is afforded for building hollow walls by using short cylinders of sheet metal, as C, which by 80 being placed in the mold before the filling in 85 is done will make hollow flues in the wall, as will be well understood. These cylinders are formed with handles, by means of which they may be readily drawn up as the work progresses.

In using concrete—that is, a mixture made of cement with broken or crushed stone—the outer face of the wall would have an unfinished or rough appearance, and to avoid this I use false moldboards D, consisting of thin 90 metal plates, in connection with the upper outside moldboard. These plates are made, preferably, of tin or other sheet metal and are of the same height substantially as the planks forming the moldboards, and at their upper 95 edges they are formed or provided with hooks h , adapted to engage with the upper edges of the top plank, so as to suspend the false moldboard therefrom at a small distance from the inner face of the outer moldboard. These 100 hooks h may be integrally formed from bent-over portions of the plates, so as to form two

depending lugs $h' h^2$, as shown. In practice these plates are hung upon the inside of the outer top plank before the concrete is filled in, and the space thus formed between the 5 two is filled in with cement, while the rest is filled in with concrete. These false mold-boards are then drawn out when it is safe to do so. Both faces of the walls, if desired, may be faced with cement in the same manner.

10 In order to give the walls the appearance of being divided in blocks, the top planks may be provided upon the inside face with vertical cleats i of triangular or square cross-section to form the desired impress. Horizontal 15 cleats i' may also be provided to form the horizontal block-divisions, or other ornamental designs may be used; but it will be observed that in such case the molds cannot be raised up bodily as a whole, but must be taken

apart and be rebuilt every time a new layer 20 is added.

What I claim as my invention is—

In molds for building composite concrete and cement walls, the combination with loose boards two or more superimposed upon each 25 other upon the inner and outer faces of the wall and held in position thereon by binders substantially as described, of false mold-boards formed with spacing-hooks upon their upper edges and adapted to be suspended 30 from the top edges of the boards forming the mold.

In testimony whereof I affix my signature in presence of two witnesses.

WILLIAM H. CADWELL.
